United States Patent Office

Des. 186,867
Patented Dec. 22, 1959

186,867

CAPELET OR THE LIKE

Byron W. Gutheil, Pasadena, Calif.

Application May 2, 1958, Serial No. 50,724

Term of patent 14 years

(Cl. D3—3)

FIG. 1.

FIG. 2.

FIG. 3.

Figure 3 is a side view thereof as it appears in wearing position; the broken line illustration of the wearer being for illustrative purposes only.

I claim:

The ornamental design for a capelet or the like, as shown and described.
